NICHOLAS S. VEDDER, OF TROY, AND TOBIAS S. HEISTER, OF LANSINGBURG, NEW YORK, ASSIGNEES TO NICHOLAS S. VEDDER.

Design No. 3,327, dated January 5, 1869.

DESIGN FOR THE PLATES OF A STOVE.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer, and State of New York, have jointly invented or produced a new and original Design for Plates of a Stove, of which the following is a full and exact description, reference being had to the accompanying photographs, in which—

Figure 1 is a side plate, and

Figure 2 an end-door plate of an elevated oven of a stove having our said design.

Our new design for the side-plate A consists essentially of the ornamental pilasters *b b*, connected by the base piece *c* and top arch *d*, bearing the vine-like ornaments *e e e*, with an internal tablet, *f*, surrounded by the ornamental moulding *g*, the whole shaped and disposed so as to appear as represented in fig. 1; and

Our new design for the door-plate H consists of the series of upright round-top sub-panels *i i i*, bearing the vine-like ornaments *e e e*, all shaped and arranged on the main panel *j j* so as to present the appearance shown in fig. 2.

What we claim as our invention or production, and desire to secure by Letters Patent, is—

The design for the plates A and H of a stove, as herein shown and described.

In testimony whereof, we have hereunto set our hands, this 8th day of December, 1868.

NICHOLAS S. VEDDER.
TOBIAS S. HEISTER.
